INVENTOR:

E. T. CURRAN,
By his Atty. John G. Seifert

UNITED STATES PATENT OFFICE.

EDWARD T. CURRAN, OF DETROIT, MICHIGAN.

WATER-HEATER.

1,295,125.

Specification of Letters Patent. Patented Feb. 25, 1919.

Application filed July 7, 1917. Serial No. 179,124.

To all whom it may concern:

Be it known that I, EDWARD T. CURRAN, a citizen of the United States, and a resident of the city of Detroit, in the county of Wayne and State of Michigan, have invented certain new and useful Improvements in Water-Heaters, of which the following is a specification.

This invention relates to water heaters, and particularly to what are termed "gas heaters" to supply a quick or instantaneous hot water supply or for a hot water heating system, and it is the object of the invention to provide a heater of this character which is simple, cheap and novel in construction and highly efficient in operation.

In the present commercial heater of this character there is provided a tubular coil, usually a spiral coil of tubing, inclosed in a shell or cylinder to constitute a heat retaining chamber with a gas burner located in such shell below the coil. In this type of heater there is considerable loss of heat due to heat radiation from the shell, and it is the principal object of the invention to provide a structure in which the radiation of the heat from the combustion of the fuel or gas is reduced to a minimum, and to provide a structure in which the water to be heated constitutes a heat retaining jacket and also the chamber for the combustion of the fuel or gas, the jacket being constructed to comprise a circuitous passage from end to end of the jacket thereby retarding the rapid flow of the water therethrough and assuring the water being heated to a high temperature.

In the drawing accompanying and forming a part of this specification Figure 1 is a vertical sectional view of a heater illustrating an embodiment of my invention.

Fig. 2 is a sectional plan view.

Fig. 3 is a plan view of a partition to separate the water jacket into superposed communicating chambers.

Fig. 4 is a sectional side elevation of the partition shown in Fig. 3 taken on the line 4-4 of Fig. 3; and

Fig. 5 is a view of a portion of the lower part of the heater looking at the right of Fig. 1 and showing means to control a secondary air supply to the burner in the combustion chamber.

Similar characters of reference designate like parts throughout the different views of the drawing.

In the embodiment of my invention shown in the drawing there are provided nested and spaced apart shells 6, 7, preferably cylindrical and dome shaped as shown, the shells at their lower ends being fixed in an annular member 8 of channel shape in cross section to close the lower end of the space between the shells. The member 8 rests upon a base 12 to support the shells and which comprises the base of the heater, said base having a door 13 to get access thereto.

The interior of the inner shell constitutes a combustion chamber C in which is located a suitable gas burner 9 to which is supplied the combustible mixture through a pipe 10 extending through an opening 11 in the shells and through which the burner may be placed into the combustion chamber, said opening having a closure 14 which may be in the nature of doors for a purpose to be hereinafter described.

The combustion chamber has an outlet for the products of combustion, such as a pipe 15 leading from the top of the combustion chamber through the shells to be connected to a flue or chimney, (not shown).

The space between the shells constitutes a jacket to contain the water to be heated, said jacket having an inlet 16 adjacent the bottom, which comprises the return pipe when the heater is utilized in connection with a heating system, and has a valved connection 17 with a water main or supply. The outlet for the jacket is at the top, as shown at 18.

The water jacket has annular partitions 19 comprising annular members split or severed transversely to provide a space or opening, as shown at 20 (Fig. 3), the annular members having lateral projecting portions 21 which are bent at right angles, as shown at 22 in dotted lines in Fig. 3 and in full lines in Fig. 4, to support and space the successive partitions from each other, as clearly shown in Fig. 1, thereby separating the jacket into superposed and communicating chambers. The partitions are so placed in the jacket that the openings 20 in successive partitions are staggered or at diametrically opposite points and remote from each other as shown in Fig. 2 thereby providing a circuitous passage for the water from end to end of the jacket.

Located in the combustion chamber C adjacent the upper end is a series of pipes or tubes 25 extending transversely of the

combustion chamber and connected at opposite ends to the water jacket, these pipes being in parallel rows with adjacent rows extending at right angles to each other as clearly shown in Figs. 1 and 2. The pipes or tubes are preferably so located that one row of tubes will communicate with one of the chambers in the jacket, and the successive rows of tubes with adjacent chambers.

10 In the operation of the heater the gas or fuel is turned on and ignited at the burner through the opening 11 by moving the door or closure 14 to open position after which the opening is closed by the door or doors 14. Should it be found that there is not a sufficient amount of air being supplied to the burner through the mixing chamber (not shown), with which all such burners are provided, a secondary air supply may be supplied to the burner in the combustion chamber by moving the closure 14 for the opening 11 to open position, or by opening the door 13 in the base, and which air supply is regulated in accordance with the opening 25 of the doors 14 or 13. As the heat increases in the combustion chamber and the water in the jacket becomes heated, which heating is greatly facilitated by the provision of the nested tubes 25, the heated water will rise and pass off through the outlet 18, but this will not take place until the water becomes thoroughly heated due to the partitions 19 which operate to retard the rising of the heated water and compels the water as it rises to take a circuitous path or course through the jacket thereby assuring the heating of the same to a high temperature. To prevent radiation of heat from the water jacket it may have a heat retaining jacket 40 or covering 27 of suitable material, such as an asbestos compound or the like.

35 Having thus described my invention, I claim:

45 1. In a water heater, nested and spaced apart dome shaped shells, the interior of

the inner shell constituting a combustion chamber and the space between the shells a water jacket having an inlet adjacent the bottom and an outlet at the top; and annular superposed partitions in the water jacket 50 to separate said jacket into superposed chambers to provide a circuitous passage from end to end of the jacket, said partitions comprising annular members extending between the inner and outer walls of the water jacket having flanges at right angles to said members to support and space successive partitions from the next lower partition, and each partition having a portion cut away to provide an opening to connect adjacent 60 chambers.

2. In a water heater, nested and spaced apart dome shaped shells, the interior of the inner shell constituting a combustion chamber and the space between the shells a 65 water jacket having an inlet adjacent the bottom and an outlet at the top; annular members to extend transversely between the walls of the jacket, each member having flanges to support and space it from the next 70 adjacent lower partition to separate said jacket into superposed chambers, and each partition having a cut away portion to provide a communicating opening between adjacent chambers whereby the partitions 75 form a circuitous passage from end to end of the jacket; and superposed rows of water tubes extending transversely of the combustion chamber with adjacent rows of tubes 80 extending at right angles to each other and the successive rows of tubes being connected to successive chambers formed by the partitions in the water chamber.

Signed at Detroit, in the county of Wayne and State of Michigan, this 14th day of 85 June, 1917.

EDWARD T. CURRAN.
